CLAIM

The ornamental design for a steaming pot for use with cooking grills, as shown and described.

DESCRIPTION

FIG. 1 is a top plan view of a steaming pot for use with cooking grills showing my new design, shown without the lid for completeness of illustration;

FIG. 2 is a top plan view with the lid positioned on the pot;

FIG. 3 is an exploded front elevational view thereof;

FIG. 4 is a bottom plan view thereof; and,

FIG. 5 is an exploded side elevational view thereof.
